CONTAINER FOR CIGARETTES AND THE
LIKE

José Fernandez Zayas, Habana, Cuba

Application May 3, 1934, Serial No. 723,746
In Cuba July 23, 1933

2 Claims. (Cl. 206—41)

This invention relates to containers for cigarettes or similar goods such as matches, tooth-picks, etc., and particularly to cigarette containers, and it has for its object the provision of certain improvements in the construction of same whereby the units of the article lodged within the container can be automatically removed by the consumer one or several at a time, without affecting the remainder of the content.

10 The invention is described with reference to the figures of the accompanying drawing, of which:

Fig. 1 is a plan view of a blank used to form the slide of the improved container.

15 Fig. 2 is a plan view of a blank used to form the outer shell of the improved container.

Fig. 3 is a perspective view of the blank represented in Fig. 1, with its portions folded and gummed to form the slide filled up, for instance, with cigarettes.

20 Fig. 4 is a perspective view of the blank represented in Fig. 2, with its portions folded and gummed to form the outer shell of the container.

Fig. 5 is a perspective view of the whole container as formed by the insertion of the slide into the outer shell.

Fig. 6 is a partly cut exterior view showing a modified position of the slide and outer shell, to illustrate the automatic removal of a cigarette.

Fig. 7 is a fragmentary top view of the outlet end of the container to show how the cigarette being removed lifts one of the holding and guiding flaps formed at the end of the slide.

And Fig. 8 is a vertical section view of the slide, showing a spring adapted to push the cigarettes toward the side wherefrom they are to be removed.

This container is composed of a slide adapted to contain such goods as cigarettes, matches, tooth-picks, etc., and of a shell open at both ends and in which is inserted the slide which is slidable within the shell when pushed by the hand of the consumer in the same manner as in many of the cigarette containers at present used. Figs. 1 and 2 show the blanks of cardboard or strawboard as provided with folding lines for its division into parts which, upon being folded and gummed one to each other, form the slide 1 and the outer shell 2 which for not forming themselves a part of the invention, will not be described in detail as their construction will be readily understood from the drawing.

The slide 1 which is provided at both ends with flaps 3 partly covering the content, has at the side 4 a cut adjacent to an angular cut 5 formed in the rear portion 6, and which extends to the end 7 and the lower flap 3, whereby it is formed

in the slide, upon the parts thereof being folded (Fig. 3), a lower lateral slot 8 the width of which will always be less than the width of one of the units of the contents, as shown in Fig. 3 in which the two side cigarettes 9 project into the slot 8 but their lower ends bear upon the end 7. Furthermore, the other end 10 of the slide shows longitudinally aligned with the slot 8, two opposed hinged flaps 11 and 12 forming holding and guiding means for the cigarette 9 when this is removed from the slide, as shown in Figs. 6 and 7.

The shell 2, which is open at both ends and which shows in its front 13 and rear portion 14 semicircular slots 15 to facilitate the push of the slide 1 by the fingers, shows at the lower edge of its side 16 adjacent to the slotted side 4 of the slide 1, a flap 17 projecting from the body of said side and the end portions 17' of which are adapted to be folded and gummed respectively upon the front 13 and upon the rear portion 14, to form an inner catch against which the units of the contents which may be adjacent to the side 16 will abut and be held thereupon.

In placing the slide 1 within the shell 2, the lateral slot 8 of the slide will stand directly above the catch 17, so that if the slide 1 is pushed downward, the cigarette or the two cigarettes 9 occupying the inner space adjacent to the side 4 will abut at one end against the catch 17 and will be held by same, and cause at the other end to open one or both hinged flaps 11 and 12, and the cigarette or cigarettes 9 will remain held by said flaps 11 and 12 and carried by same when the slide 1 be pushed again, but now in a contrary direction, to return it to its normal position within the shell 2. In such arrangement, the cigarette or cigarettes will come out from the shell 2, as shown in dotted lines in Fig. 6 of the drawing, thus enabling the consumer to remove them from the container.

The slide 1 could be provided with a sheet spring bent in zig-zag 18, placed near the side opposite to the side 4, to force the contents to be held in contact with the side 4, but such spring is not necessary, as it will be sufficient to maintain the container in an inclined position in order that the contents may by gravity stand close to the cut side 4.

The return of the slide to its normal position within the shell 2 could also be made automatically, without need to push it for the second time as above described, by the use of a resilient means to connect the slide 1 to the shell 2, but such resilient means is also unnecessary.

The removal of the articles can be made in one

unit or in two or more, according to the position of the units in their adjacent rows within the slide.

This container can be also made of leather, wood, metal or any other material which would be suitable for the purposes.

What I claim is:

1. A container for cigarettes and the like, comprising a slide, an outer shell open at both ends and within which is inserted the slide, the slide having a slotted section at one side which extends to an end of the slide, two opposed hinged flaps cut at the other end of the slide and longitudinally aligned with the slotted section of same, an inner catch formed by a strip projecting from the side of the shell adjacent to the slotted section of the slide and the end portions of which are folded and stuck upon the front and the rear portion of the shell, so that the catch may hold one or several units of the contents in the slide upon the latter being pushed out from the slotted end of the shell, and upon the slide returning to its normal position within the shell, the hinged flaps of the slide may carry said unit or units held by the catch outside of the shell for removal by the consumer.

2. A container for cigarettes and the like, comprising a slide, an outer shell open at both ends and within which is inserted the slide, the slide having a slotted section at one side which section extends to an end of the slide and is of a smaller width than the width of a unit of the contents, two opposed hinged flaps cut at the other end of the slide and longitudinally aligned with the slotted section of same, an inner catch formed by a strip projecting from the side of the shell adjacent to the slotted section of the slide and the end portions of which are folded and stuck upon the front and the rear portion of the shell, so that the catch may hold one or several units of the contents in the slide upon the latter being pushed out from the slotted end of the shell, and upon the slide returning to its normal position within the shell, the hinged flaps of the slide may carry said unit or units held by the catch outside of the shell for removal by the consumer.

JOSÉ FERNANDEZ ZAYAS.
